COMBINED ROTATABLE TELEPHONE STAND,
AND PENCIL AND NOTE HOLDER OR SIMILAR ARTICLE

Earl A. Strang, Waukegan, Ill.

Application December 7, 1955, Serial No. 39,187

Term of patent 3½ years

(Cl. D26—14)

Fig. 5.

Fig. 1 is a top plan view of a combined rotatable telephone stand, and pencil and note holder or similar article, showing my new design;

Fig. 2 is a side elevational view thereof;

Fig. 3 is a front elevational view thereof;

Fig. 4 is a bottom plan view thereof; and

Fig. 5 is a perspective view thereof, to an enlarged scale.

I claim:

The ornamental design for a combined rotatable telephone stand, and pencil and note holder or similar article, substantially as shown.
